(57) CLAIM

An ornamental design for a glass tile array, as shown and
described.

DESCRIPTION

FIG. 1 is a first end elevation view of one end of the glass
tile array;

FIG. 2 is a top plan view the embodiment of FIG. 1; and

FIG. 3 is a side elevation view of the opposite end; and,

FIG. 4 is a side elevation view, the opposing side elevation
view being substantially a mirror-image thereof.
